SHEET HANDLING MECHANISM

Earl R. Muddiman, Wilkinsburg, Pa., assignor
to Carnegie-Illinois Steel Corporation, a corpo-
ration of New Jersey

Application December 18, 1944, Serial No. 568,709

6 Claims. (Cl. 198—28)

1

This invention relates to an improvement in sheet handling and conveying apparatus. More particularly, it relates to a sheet conveying mechanism wherein separate sheets traveling at high speed are either reduced in speed or brought to rest to permit subsequent operations.

Among the objects of the invention is the provision of an improved sheet conveyor mechanism adapted for use where the speed of travel of a series of separate sheets must be reduced.

A further object is the improvement of such type of conveyor whereby damage to the conveyor mechanism by the sheets is avoided, and wherein bending or cobbling of the sheets is precluded.

These and further objects of the invention will more clearly appear in the subsequent description.

Certain processes carried out upon sheet material, such as sheet metal, involve the transportation of the separate sheets sequentially on a high speed conveyor. It is frequently necessary, in order to perform subsequent steps on the sheets, to markedly reduce their speed and, in some cases, to bring them to a complete stop. The sheet classifier and piler shown and described herein is typical of apparatus requiring such change of speed. It is to be understood, however, that the invention is not confined to being used with a sheet classifier and piler, but that it finds utility wherever sheets traveling at relatively high speed on a conveying device are materially slowed in their travel by being transferred onto a subsequent conveying device traveling at a markedly lower speed.

The invention will be more readily understood by reference to the accompanying drawings, in which:

Figure 1 is a view in side elevation of a sheet classifier and piler in which the device of the present invention is employed;

Figure 2 is a view in side elevation of that portion of the apparatus shown in Figure 1 at the classifier, certain parts thereof having been shown in section;

Figure 3 is a view in cross section of the classifier said section being taken along the line III—III of Figure 2;

Figure 4 is a view in section of the classifier, said section being taken along the line IV—IV in Figure 2; and

Figure 5 is a view in vertical section of the bottom portion of the classifier, certain parts being omitted for clarity.

The sheet classifier and piler, shown in Figure

2

1, consists of an entering driven belt conveyor 2 constituting an inspection table. Conveyor 2, in the modification shown, is made up of a series of V-belts 3 located side by side and running over pulleys 4 and 6. The conveyor 2 is driven by means, subsequently to be described, through shaft 8 upon which pulleys 6 are fixed. Separate sheets, deposited upon conveyor 2 in spaced relationship by means not a part of this invention, are carried at high speed by the conveyor into the classifier unit, which is indicated generally by reference character 10. The classifier unit consists of a main frame 12 in which are journaled power-driven pinch rolls 14, the bite of which is located approximately on the level with the top of conveyor 2 and adjacent to the exit end of such conveyor, so that pinch rolls 14 grasp the sheets as they leave the conveyor. Also journaled in frame 12 is a classifier gate 16 having a triangular vertical section, as shown in Figure 2. The forward point of the gate extends near the rear of the bite of pinch rolls 14, so as to act as a guide for the sheets immediately as they leave the pinch rolls.

20 Gate 16 may be oscillated in a vertical plane throughout a small angle. In its downward position, shown in full lines in Figure 2, the gate functions to cause the sheets to travel on its upper surface, and thus the gate guides the sheets into the upper or prime conveyor line. In its upper position, shown in dotted lines in Figure 2, gate 16 deflects sheets leaving rolls 14 down into the lower or reject conveyor line.

25 Gate 16 may be selectively positioned by means of solenoid 18, said solenoid being operated either by an operator who watches the sheets as they pass on conveyor 2, or by automatic gauging or inspecting means which energizes the solenoid to swing the gate into its upper position at the proper time to cause the non-conforming sheet to be diverted into the lower, reject conveyor line. A typical automatic gauging means and circuit satisfactory for operating solenoid 18 is disclosed in the patent to Terry, No. 2,007,840, 30 dated July 9, 1935.

35 Prime sheets after riding over the upper surface of gate 16 pass through a photoelectric counting means 20 and into power-driven exit pinch rolls 22, which are driven at the same peripheral speed as conveyor 2 and entrance pinch rolls 14. Sheets leaving pinch rolls 22 fall upon prime conveyor 24, in the form of parallel driven belts, which is driven at a speed materially lower than the speed of conveyor 2, 40 for instance on the order of one-half of such

speed. Conveyor 24 is driven by means to be described through shaft 26, upon which pulleys 21 carrying the conveyor belts are located, at the entrance end of the conveyor. Because the conveyor 24 travels at a materially lower speed than the exit pinch rolls 22, the sheets fall upon the conveyor 24 in overlapping or shingled relationship and are carried in that condition to the prime piler, indicated generally at 30, where they are brought to rest and stacked in a pile.

When gate 16 is in its upper position, sheets traveling through pinch rolls 14 are deflected downwardly into the lower or reject conveyor line. Such conveyor line consists of a driven belt conveyor 34, made up of two parallel belts 35, running side by side over pulleys 36 at the entering end of the conveyor, and over pulleys 38 at the exit end of the conveyor. The conveyor 34 is driven by power applied to shaft 37 to which pulleys 36 are affixed. Conveyor 34 is likewise driven at a speed materially lower than that of conveyor 2 and pinch rolls 14, for example on the order of one-half such speed. Rejected sheets carried by conveyor 34 travel away from the classifier and into reject piler 39, where they are brought to rest and stacked into a pile.

Power for driving the various conveyors and pinch rolls of the device is supplied by motor 40, which drives speed change device 41. Entering conveyor 2 is driven by chain 42 which runs over a sprocket on shaft 8 of the conveyor and a sprocket connected to the drive pulley of the speed change device 41. Pinch rolls 14 and 22 are driven by chains running over sprockets on shaft 8 of conveyor 2, the driving and driven sprockets being such that the pinch rolls have the same peripheral speed as the conveyor. Prime conveyor 24 and reject conveyor 34, however, are driven by the variable speed output shaft of the speed change device 41 by means of drive chain 45 which drives the reject conveyor 34 and drive chain 44 connecting the reject conveyor to the prime conveyor 24. By such arrangement the speeds of the prime and reject conveyors relative to the entering conveyor and the pinch rolls in the classifier may be varied at will by variation of speed change device 41.

Rejected sheets traveling downwardly from pinch rolls 14 take the path indicated by the curved dotted line shown in Figure 2. Such sheets travel at the same speed as pinch rolls 14 when engaged by such rolls, and when the forward end of a sheet strikes the upper surface of reject conveyor 34, which is traveling at a much lower speed than the sheet, such forward end of the sheet tends to dig in and cut the reject conveyor. Furthermore, what is even more serious, the sheet has a tendency to bend over on itself and to cobble, particularly if the rear of the sheet is still engaged by pinch rolls 14, thus jamming the conveyor mechanism.

The present invention overcomes such tendencies of the sheets to damage themselves and the conveyor, when thus fed downwardly and suddenly materially slowed in speed, by providing a skid member 46, which, in the modification shown, is in the form of a plate which overlaps to some extent the entering end of the reject conveyor. Skid 46 is placed slightly above the surface of conveyor 34, and is adjustable longitudinally of the conveyor to accommodate the feeding of sheets of different lengths through the device. The purpose of such skid member is to intercept the forward end of the rejected sheet as it is fed downwardly to prevent its striking the top of the

reject conveyor directly. The forward end of the sheet is then slowed by sliding along the end of skid 46 for a short distance, after which it runs off the skid into contact with conveyor 34. Preferably skid 46 is adjusted so that its forward end is at such a distance from pinch rolls 14 that sheets of the particular length being fed leave the pinch rolls before their forward ends contact the reject conveyor. By such arrangement the sheets are slowed sufficiently so that they do not tend to double on themselves when they contact the reject conveyor. Furthermore, the contact of the forward end of the sheets with the conveyor is not at a material angle with the consequent tendency to dig in, as is the case in the absence of skid 46, but on the contrary such contact is tangential and still further slows the sheets to coincidence with the speed of the reject conveyor without buckling them. When the rear end of the sheet leaves rolls 14, it falls upon inclined skid 47, and is guided thereby downwardly onto skid 46.

The skid or plate 46 has affixed thereto, as by welding, side members 48 to the bottom of which are attached rack gears 50. The side portions of members 48 are guided in longitudinal slots in the side frame members 52 attached to the frame of the classifier mechanism at the rearward part thereof. At its forward end skid 46 is supported by resting at the sides upon angular members 72 attached to side members 78 affixed to the forward part of the frame of the classifier. Longitudinal adjustment of the skid 46 is effected by means of pinions 60 meshing with the racks 50, said pinions being keyed upon transverse shaft 54, which is supported in bearing 56 at the right hand side of the frame, as shown in Figure 3, and in a bearing composed of sleeves 58 and 65, at the left hand side of the frame. Rotation of shaft 54 is accomplished by handwheel 62 which is splined to the left hand end of shaft 54, which is of a reduced diameter. Shaft 54 may be clamped in any desired position by tightening knurled nut 64 screwed onto the end of the reduced portion of the shaft, such tightening of the nut having the function of sliding the handwheel against part of the left hand bearing, thereby clamping the shaft and preventing its rotation.

In order to support the central portion of the skid 46 against deflection under load, it is provided on the under side thereof with a longitudinally extending bar 66 which is welded thereto and which slides upon the centrally located tubular member 68 attached to the frame 70 of the reject conveyor. In order to limit the forward extension of skid 46, there are provided stops 74 in line with the racks 50, such stops extending downwardly so that they contact the pinions 60 when skid 46 is advanced all the way to the right. The extent of rearward travel of skid 46 is determined by the upstanding stationary stop 76 (see Figure 5) which contacts the rearward end of the central longitudinal bar 66 on skid 46 when the skid is fully retracted as shown in Figure 5.

Although one embodiment of the invention has been described for purposes of illustration, it is to be understood that numerous variations may be made by those skilled in the art within the scope of the present invention. Thus, although the skid 46 has been illustrated as being in the form of a plate, it can be made in the form of a plurality of spaced parallel rail-like members having a substantial sheet contacting area. Similarly other equivalent known means, such as a

screw and nut, may be employed to adjust the skid longitudinally of the conveyor.

Having thus fully described the invention and its manner of operation, I desire to claim as new the following:

1. Sheet handling and conveying apparatus comprising a driven sheet conveyor, power driven means for feeding separate sheets sequentially thereto so that the forward ends of the sheets fall freely toward the conveyor, and skid means lying above the top surface of the conveyor and generally parallel thereto in a position to receive directly the forward ends of the sheets as they are fed toward the conveyor, said skid means being adjustable longitudinally of the conveyor to accommodate sheets of different lengths.

2. Sheet handling and conveying apparatus comprising a driven sheet conveyor, means for feeding separate sheets sequentially downwardly toward the top surface of the conveyor, said sheet feeding means causing the sheets to travel at a rate materially greater than the speed of the conveyor, skid means partly overlapping the entering end of the conveyor and lying slightly above and generally parallel to the top surface of the conveyor in a position to receive directly the forward end of a sheet as it is fed downwardly, and means for adjusting the skid means longitudinally of the conveyor to accommodate sheets of different lengths.

3. Sheet handling and conveying apparatus comprising a driven belt conveyor, means above said conveyor for feeding separate sheets sequentially downwardly toward the top surface of the conveyor, said sheet feeding means causing the sheets to travel at a rate materially greater than the speed of the belt conveyor, skid means partly overlapping the entering end of the conveyor and lying slightly above and generally parallel to the top surface of the conveyor, and means to adjust the skid means longitudinally of the conveyor.

4. Sheet handling and conveying apparatus comprising a driven sheet conveyor, means above said conveyor for positively feeding separate sheets sequentially downwardly toward the top surface of the conveyor, said sheet feeding means causing the sheets to travel at a rate materially greater than the speed of the belt conveyor, skid means partly overlapping the entering end of the conveyor and lying slightly above and generally parallel to the top surface of the conveyor, and

means to adjust the skid means longitudinally of the conveyor, said skid being so adjusted relative to the means above the conveyor for feeding sheets downwardly toward the belt conveyor that with the particular length of sheets being fed the forward ends of the sheets strike the skid means near the forward end thereof, and so that the rear ends of the sheets leave the first named sheet feeding means before the forward ends thereof contact the surface of the conveyor.

5. Sheet handling and conveying apparatus comprising a driven belt conveyor for the sheets, driven pinch rolls above said conveyor for positively feeding separate sheets sequentially downwardly toward the top surface of the conveyor, said pinch rolls causing the sheets to travel at a rate materially greater than the speed of the belt conveyor, sheet supporting skid means partly overlapping the entering end of the conveyor and lying slightly above and generally parallel to the top surface of the conveyor, and means to adjust the skid means longitudinally of the conveyor, whereby the forward ends of the sheets strike the skid means near the forward end thereof and slide therealong into contact with the belt conveyor, the skid means being so adjusted that the rear ends of the sheets leave the pinch rolls before the forward ends thereof contact the conveyor.

30. 6. Sheet handling and conveying apparatus comprising a driven belt conveyor for the sheets, power-driven pinch rolls above the conveyor for positively feeding separate sheets sequentially downwardly toward the top surface of the conveyor, said pinch rolls causing the sheets to travel at a rate materially greater than the speed of the belt conveyor, sheet supporting skid means in the form of a plate of a width at least equal to that of the sheets, said plate partly overlapping the entering end of the conveyor and lying slightly above and generally parallel to the top surface of the conveyor, and means to adjust the plate longitudinally of the conveyor, whereby the forward ends of the sheets strike the plate near the forward end thereof and slide therealong into contact with the belt conveyor, the plate being so adjusted for the length of sheets fed that the rear ends of the sheets leave the pinch rolls before the forward ends thereof contact the belt conveyor.

EARLL R. MUDDIMAN.
